DESIGN.

C. D. FOSTER,

CARD BACK,

APPLICATION FILED JUNE 23, 1921.

60,721.

Patented Mar. 28, 1922.

Inventor
Charles D. Foster

UNITED STATES PATENT OFFICE.

CHARLES D. FOSTER, OF KANSAS CITY, MISSOURI.

DESIGN FOR A CARD BACK.

•60,721.

Specification for Design. Patented Mar. 28, 1922.

Application filed June 23, 1921. Serial No. 479,939. Term of patent 3½ years.

To all whom it may concern:

Be it known that I, CHARLES D. FOSTER, a citizen of the United States, residing at Kansas City, in the county of Jackson and State of Missouri, have invented a new, original, and ornamental Design for Card Backs, of which the following is a specification, reference being had to the accompanying drawing, forming part thereof.

The figure is a plan view of a card back, showing my new design.

I claim:

The ornamental design for a card back, as shown.

CHARLES D. FOSTER.
